JOSEPH P. DALY, OF SYRACUSE, NEW YORK, ASSIGNOR TO THE PROSPERITY COMPANY INC., OF SYRACUSE, NEW YORK, A CORPORATION OF NEW YORK

GARMENT OR IRONING PRESS

Application filed July 9, 1926, Serial No. 121,306. Renewed May 6, 1931.

This invention relates to pressing machines, such as garment and laundry pressing or ironing machines and has for its object a particularly simple and efficient power actuating mechanism to actuate one of the press jaws, and more particularly a power mechanism embodying a reciprocating actuator, as the piston rod of a piston movable in a cylinder; it further has for its object a particularly simple and efficient means for controlling the flow of motive fluid to the cylinder in such a way that the movable pressing element or head must be preliminarily closed by hand before the motive fluid can be admitted to the cylinder, and the preliminary closing movement of the head is independent of the actuator, and does not move the actuator so that the full power stroke of the piston is utilized in applying pressure.

The invention consists in the novel features and in the combinations and constructions hereinafter set forth and claimed.

In describing this invention reference is had to the accompanying drawings in which like characters represent corresponding parts in all the views.

Figure 1 is a side elevation of a machine embodying my invention.

Figure 2 is a detail sectional view of the manual control valve shown in open-press position.

Figure 3 is a detail sectional view of the cut off valve automatically operated by a movable part of the machine.

Figure 4 is a detail fragmentary view of the cylinder and piston movable therein.

Figure 5 is a sectional view of the press frame on line 5—5, Figure 1, parts being omitted.

I have here illustrated my invention as embodied in a conventional type of garment and laundry pressing machine comprising press jaws such as a buck 1 and a head 2 movable toward and from the buck, the buck being carried by a goose neck 3, which in turn is mounted on a frame 4. The head 2 is carried by a yoke or lever 5 pivoted at 6 between its ends to a standard 7 rising from the frame, and said lever carries the head 2 at its front end, and is connected at its rear

end to the actuating mechanism. A suitable handle 8 is mounted on the front of the yoke by means of which the head 2 is preliminarily closed by hand, a counter weight 9 tending to open the press being mounted on the rear end thereof.

10 is the cylinder and 11 the piston movable in the cylinder and having a rod 12, the piston and its rod constituting a reciprocating actuator. The cylinder is mounted in the rear leg 13 of the machine of which the standard 7 is an upward extension and is pivoted at 12a therein so as to have an operating movement. The rear leg is in the form of a channel. It will be understood that the frame has but a single rear leg centrally located.

The motion transmitting mechanism between the actuator 12 and the yoke lever 5, as here shown, includes a part with which the actuator or rollers 14 at its ends has sliding connection, this part being a lever 15 pivoted between its ends at 16 to the frame, and having one arm pivoted at 17 to the lower end of a link 18, the upper end of which is pivoted at 19 to the yoke lever, the other arm of the lever 15 coacting with the rollers 14 which rollers slide or move lengthwise of the lever from its axis toward the outer end of the lever during the power stroke.

Each of the rollers 14 is guided in its movement by a cam slot 20 formed in the frame, there being two cam slots, one in each of the side flanges of the rear leg. The cam slot is so arranged that as the roller 14 moves from its point nearest the axes 16 of the lever toward the outer end of the lever, the roller first has a slight rearward movement owing to a forward deflection 21 at the upper end of the slot 20, and thereafter it slides along the lever 15 in a nearly vertical portion of the slot, the lever being inclined relatively to the slot, so that a long movement of the piston is transferred into a short movement of the lever 15, and finally as the roller approaches the end of the arm 15, it takes an abrupt rearward movement to apply the final pressure due to a rearward deflection 22 at the lower end of the slot 20. Owing to the sliding connection between the reciprocating

actuator or piston rod 12 and the part or lever 15, the head can be preliminarily closed without requiring any movement of the actuator 12 so that the full throw of the actuator 12 is utilized in applying the final heavy pressure, and the long throw of the actuator is converted into power or a short movement of the lever 15 due to the movement of the actuator 12 or its follower 14 lengthwise of the lever.

Motive fluid as steam or air is supplied to the cylinder from a suitable source of supply through a pipe 23 and is controlled in its flow to and from the cylinder 10 by a valve 24 having a manually operated handle 25. The piston here shown is double acting and in operation the motive fluid enters the pipe 23 and past an automatic safety means comprising a cut out valve 26 to be presently described, then through a pipe 27 to the intake port 28 in the valve casing of a valve 24, thence through the passage 29 of the core or movable member 30 of said valve, through port 31 and a pipe 32 to the upper end of the cylinder so that the piston is depressed to the full end of its throw. During such movement of the piston the fluid exhausts from the lower end of the cylinder through pipe 33, port 34 of the exhaust valve 24, valve 30 passage 35 of the valve 30 and out through the exhaust port 36. To open the press, the valve member 30 is moved by the handle 25 into the position shown in Figure 2 so that the air enters the bottom of the cylinder 35 through pipe 37, port 38, passage 35, out through port 34, and at the same time the air exhausts from the top of the cylinder through the pipe 32, port 31, valve passage 29 and exhaust passage 38.

40 The safety valve means 26 shown in Figure 3 is a one way valve normally in closed position when the press is open, and arranged so that its passage is brought into alignment with the pipes 23 and 27 only after the head 45 2 has been preliminarily closed so that ordinarily the motive fluid from feed pipe 23 cannot be led into the cylinder unless the head has been preliminarily closed. The valve 26 is a rotary valve, the rotatable part of which 50 has a rock arm 40 thereon which is connected by a link 41 to the rear arm of yoke lever 5; thus power can be applied to the head only after it has been brought down to preliminary closed position by hand. The head can 55 be opened at any time by operating the control valve handle 25 so as to permit the air to exhaust from the upper end of the cylinder, and enter the lower end through the pipe 37. The press head is opened as the piston 60 moves upwardly in the cylinder by the counterweight 9 and countersprings.

This machine is particularly advantageous in that it provides a way by which in a machine operated by a cylinder the head must 65 be preliminarily closed by hand, and another

handle operated to apply the power and by which the power cannot be applied until the head has been preliminarily closed by hand. Also the full stroke of the piston is utilized to apply pressure and no part of the stroke utilized to preliminarily close the press.

It is therefore seen that an ironing press is produced which is safe in operation in that a safety valve means 26 functions to render the control handle 25 ineffective until after the press head has reached safe position on the buck. The valve 26 may be a one-way valve means, as shown in the illustrated example of the invention, and thru which a flow of air takes place toward the front of the press to the valve and handle means 24-25, to render the latter effective to produce heavy pressure between the jaws 1 and 2 only after the press has closed. The one-way safety-valve means 26 may be operatively connected with the press lever 5 and automatically opened thereby after the head reaches the buck.

Thus the press head 2 is capable of being closed or moved toward the buck without in any way being under the driving force of the heavy pressure cylinder 10. The one-way safety valve means 26 cuts out the power cylinder 10 until it is safe to admit air pressure to the motor means 10.

What I claim is:

1. In a pressing machine, cooperating pressing elements, one of which is movable toward and from the other, the movable element having a handle associated therewith by which it is preliminarily closable toward the other, means for applying pressure to the movable element after it has been preliminarily closed comprising a cylinder, a piston movable in the cylinder, motion transmitting parts movable with the movable element during its preliminary closing movement independently of the piston, and means for controlling the flow of motive fluid to and from the cylinder including a conduit having a normally closed valve therein, and connections between said valve and the movable element whereby the preliminary closing movement of the movable element opens the valve.

2. In a pressing machine, cooperating pressing elements, one of which is movable toward and from the other, the movable element having a handle by means of which it is moved preliminarily toward closed position, means for actuating the movable element including a cylinder, a piston having a piston rod movable in the cylinder, motion transmitting means between the piston rod and the movable element, a manually operated valve arranged to control the flow of motive fluid to and from the cylinder, a second normally closed valve for controlling the flow of motive fluid to the cylinder, the second valve being normally closed and movable into open position by the preliminary closing move-

ment of the movable element by said handle, and connections between the second valve and the movable element whereby the preliminary closing movement of the movable element by the handle opens said valve and the opening of said movable element closes said valve.

3. In a pressing machine cooperating pressing elements, one of which is movable toward and from the other, the movable element having a handle associated therewith by which it is preliminarily movable toward the other into closed position, power mechanism for applying pressure to the movable element including a cylinder, a piston movable in the cylinder, means for controlling the supply of motive fluid to the cylinder to apply pressure to the movable element including a conduit for the motive fluid, a normally closed valve in said conduit and connected to the movable element to be operable into open position by the movable element during the movement thereof by the handle and into closed position by the opening movement of the movable element.

4. In a pressing machine, cooperating pressing elements, one of which is movable toward and from the other, the movable element having a handle associated therewith by which it is preliminarily movable from open toward closed position, means for applying pressure to the movable element after it has been preliminarily closed comprising a cylinder, a piston having a piston rod movable in the cylinder, motion transmitting means between the piston rod and the movable element including a part with which the piston rod has a sliding engagement said part extending at an angle to the direction of the piston and the piston sliding lengthwise of said part.

5. In a pressing machine cooperating pressing elements, one of which is movable toward and from the other, the movable element having a handle associated therewith by which it is preliminarily movable from open toward closed position, means for applying pressure to the movable element after it has been preliminarily closed comprising a cylinder, a piston having a piston rod movable in the cylinder and having a cam follower, motion transmitting means between the piston rod and the movable element including a part with which the piston rod has a sliding engagement and a cam engaging the follower of the piston rod for guiding the rod during its movement.

6. In a pressing machine cooperating pressing elements, one of which is movable toward and from the other, the movable element having a handle associated therewith by which it is preliminarily movable from open toward closed position, means for applying pressure to the movable element after it has been preliminarily closed comprising a cyl-

inder, a piston having a piston rod movable in the cylinder and having a cam follower, motion transmitting means between the piston rod and the movable element, including a lever, the piston rod having a follower movable lengthwise of the lever, and a stationary cam engaging the follower of the piston rod for guiding it during its movement.

7. In a pressing machine cooperating pressing elements, one of which is movable toward and from the other, the movable element having a handle associated therewith by which it is preliminarily movable toward closed position, a yoke lever supporting the movable element, a link pivoted to the yoke lever, a motion transmitting lever pivoted between its ends and one arm thereof being pivoted to the link, and a reciprocating actuator coacting with the other arm of the lever and having a sliding connection therewith.

8. In a pressing machine cooperating pressing elements, one of which is movable toward and from the other, the movable element having a handle associated therewith by which it is preliminarily movable toward closed position, a yoke lever, a supporting frame supporting the movable element, a link pivoted to the yoke lever, a motion transmitting lever pivoted between its ends and one arm thereof being pivoted to the link, and a reciprocating actuator coacting with the other arm of the lever and having sliding connection therewith, the frame being formed with a cam slot, and the actuator having a follower movable along the slot.

9. In a pressing machine cooperating pressing elements, one of which is movable toward and from the other, the movable element having a handle associated therewith by which it is preliminarily closeable toward the other, means for applying pressure to the movable element after it has been preliminarily closed comprising a cylinder, a double acting piston movable in the cylinder and motion transmitting parts between the piston rod and the movable element, pipes for conducting a motive fluid to and from opposite ends of the cylinder, a manually operable valve for controlling flow of motive fluid through said pipes and a normally closed cut out valve in the intake pipe leading to the end of the cylinder into which the motive fluid enters to apply pressure to the movable element, and connections between said cut out valve and the movable element by which said cut out valve is opened by the preliminary closing movement of the movable element.

10. In a pressing machine, cooperating pressing elements, one of which is movable toward and from the other, the movable element having a handle associated therewith by which it is preliminarily movable from open toward closed position, means for applying pressure to the movable element after it has been preliminarily closed comprising a cyl-

- inder, a piston movable in the cylinder and having a piston rod, motion transmitting means between the piston rod and the movable element including a lever, the piston rod 5 having a follower movable lengthwise of the lever, the lever having a part extending at an angle to the direction of movement of the piston rod, and the follower sliding lengthwise of said part.
- 10 11. In a pressing machine, cooperating pressing elements, one of which is movable toward and from the other, operator-operated means for preliminarily closing the movable element, means for applying pressure to the movable element after it has been preliminarily closed comprising a fluid operated motor, a feed line for the motive fluid, a normally closed valve, a manually operable valve in series in the feed line, and means operated by the preliminary closing movement of the movable element to open the normally closed valve.
- 15 12. A pressing machine comprising a frame, cooperating pressing elements, one of which is movable toward and from the other, actuating means for the movable element comprising a reciprocating actuator having a follower, a motion transmitting lever between the actuator and the movable element 20 along which lever the follower moves, and a stationary cam for guiding the follower in its movement.
- 25 13. A pressing machine comprising a supporting frame, cooperating pressing elements, one of which is movable toward and from the other, a reciprocating actuator, motion transmitting connections between the actuator and the movable element including a lever normally standing at an angle to the 30 direction of movement of the actuator when the press is open and movable toward a position parallel to the actuator during the closing of the press, the actuator having a follower movable along the lever during the actuating movement thereof, and a stationary 35 guide for the actuator.
- 40 14. A pressing machine comprising a frame having a rear leg in the form of a channel, cooperating pressing elements, one of which is movable toward and from the other, the latter being carried by the frame, a lever carrying the former element and pivoted to the rear leg, a reciprocating actuator located in the channel of the rear leg, motion transmitting means between the actuator, and said lever including a part extending into the channel of the rear leg to coact with the actuator.
- 45 15. A pressing machine comprising a frame having a rear leg in the form of a channel, cooperating pressing elements, one of which is movable toward and from the other, the latter being carried by the frame, a lever carrying the former element and pivoted to the rear leg, a reciprocating actuator located
- 50 in the channel of the rear leg, motion transmitting means between the actuator and said lever including a member pivoted between the side walls of the channel of the rear leg and having an arm extending into the channel, the actuator having a follower movable along said arm, and the side walls of said channel being provided with guides for the follower.
- 55 16. In a pressing machine, cooperating pressing elements, one of which is movable toward and from the other, a yoke lever supporting the movable element, a link pivoted to the yoke lever, a motion transmitting lever pivoted between its ends, one arm thereof being pivoted to the link and a reciprocating actuator coacting with the other arm of the lever and having a sliding connection therewith, and the lever being normally arranged at an angle to the reciprocating actuator and movable by the actuator into a position parallel to the actuator.
- 60 17. In a pressing machine, cooperating pressing elements, one of which is movable toward and from the other, a yoke lever supporting the movable element, a link pivoted to the yoke lever, a motion transmitting lever pivoted between its ends, one arm thereof being pivoted to the link, and a reciprocating actuator coacting with the other arm of the lever and having a sliding connection therewith, a stationary guide for the actuator, and a cam face in said stationary guide.
- 65 18. A garment or ironing press comprising a frame, coacting press jaws, an upright cam-way formed in the frame and including a lower rearwardly directed cam-way, a fluid motor mounted in the frame above the cam-way, a connecting rod extending downwardly and carrying a follower which runs in the cam-way, an upright lever pivoted on the frame adjacent the upright cam-way and extending across said cam-way when the press is open, the lower end of the lever reaching beyond the rearwardly directed cam-way when the press is closed, an operating connection between the lever and one of the press jaws to actuate the latter, and pressure feed and valve means connected with the motor to operate same, whereby the follower travels down the cam-way riding against the lever and moving rearwardly as the press closes to produce high jaw pressure.
- 70 19. A garment or ironing press comprising a frame, press jaws including a press buck mounted on the frame, a press head above the buck and adapted to be moved toward and into engagement with the buck without danger to the operator, a fluid pressure cylinder and piston operatively connected with the press head, a pressure feed line connected with the cylinder, a manually-controlled valve included in the pressure feed line and disposed at the front of the
- 75 80 85 90 95 100 105 110 115 120 125 130

- press and normally inoperative to admit pressure to the cylinder when the press is open, a one-way safety-valve means operatively connected with the press lever and
- 5 automatically opened after the press head reaches the buck, and a pressure conduit interconnected between the one-way safety-valve means and the manually-controlled valve at the front of the press by which fluid
- 10 pressure flows from the former valve to the latter valve to render said manually-controlled valve operative, whereby an operator may actuate the manually-controlled valve to admit pressure to the cylinder only after
- 15 the one-way safety-valve means is opened and thereby safely produce final high jaw compression.

20. A garment or ironing press comprising a frame, press jaws including a press buck mounted on the frame, a press head above the buck and adapted to be moved toward and into engagement with the buck without danger to the operator, a fluid pressure cylinder and piston operatively connected with the press head, a pressure feed line connected with the cylinder, a manually-controlled valve included in the pressure feed line and normally inoperative to admit pressure to the cylinder when the press is

25 open, a one-way safety-valve means operatively connected with a movable part of the press and automatically opened after the press head reaches the buck, and a pressure conduit interconnected between the one-way

30 safety-valve means and the manually-controlled valve by which fluid pressure flows from the former valve to the latter valve to render said manually-controlled valve operative, whereby an operator may actuate the

35 manually-controlled valve to admit pressure to the cylinder only after the one-way safety-valve means is opened and thereby safely produce final high jaw compression.

In testimony whereof, I have hereunto
45 signed my name, at Syracuse, in the county
of Onondaga and in the State of New York,
this 28th day of June, 1926.

JOSEPH P. DALY.
